ATTORNEY

UNITED STATES PATENT OFFICE.

JOHN F. STARK, OF NEW HAVEN, PENNSYLVANIA.

GAS-LEAK DETECTOR.

SPECIFICATION forming part of Letters Patent No. 406,241, dated July 2, 1889.

Application filed March 27, 1889. Serial No. 304,932. (No model.)

To all whom it may concern:

Be it known that I, JOHN F. STARK, of New Haven, in the county of Fayette and State of Pennsylvania, have invented a new and useful Improvement in Gas-Leak Detectors, of which the following is a full, clear, and exact description.

This invention has for its object the production of a simple, cheap, and efficient instrument for use as a gas-leak detector in houses and elsewhere where gas is used, whereby both lives and property may be saved.

The invention consists in a novel device in which phosphorus is used in connection with wire-gauze within a glass or transparent tube open below, but having a cover on its top, and provided above or on its top with a wire-gauze-covered opening, substantially as hereinafter described, and pointed out in the claims.

Reference is to be had to the accompanying drawings, forming a part of this specification, in which similar letters of reference indicate corresponding parts in all the figures.

Figure 1 represents an exterior vertical view of an instrument embodying my invention; Fig. 2, an upper end view or plan of the same; Fig. 3, a central vertical section thereof, and Fig. 4 a transverse section of the same upon the line $x-x$ in Fig. 3.

30 A indicates a glass or other transparent tube open at its one or lower end.

B is a piece of stiff wire, having secured to its lower end a series, preferably three or more, of wire-gauze disks b, arranged one on top of the other and of a size to fit closely, by their elasticity, within the tube A. The other or upper end of this wire, which latter only projects a certain distance down within the tube A, is secured to a metal or other close cap C, made 40 to fit in a removable manner the upper end of the tube. This cap is provided with a small opening c, closed by a wire-gauze d. Prior to passing the wire B, with its attached wire-gauze disks b, down into the tube and closing the

45 upper end of the latter by the cap C, a few fragments of phosphorus e are placed upon the upper surface of the combined disks b, which collectively form a phosphorus support or table. The tube A is now placed in another 50 tube filled with water, or water and alcohol, in which the instrument may be kept when not in use.

To use the instrument, the tube A is lifted from the water, or water and alcohol, and in a few moments becomes filled with a cloud of phosphorous acid, and if it be exposed in a room or elsewhere where there is a leakage of gas, even if only a small one, the gas entering the open end of said tube A will cause the latter to be instantly cleared and the slow 60 combustion of the phosphorus will be stopped.

When the instrument is used in the dark, a white light will be seen glowing in the tube, which instantly disappears when escaping gas is let onto it.

The instrument will work at all or most temperatures—say from 66° to 100° Fahrenheit. Below 66° it will work in the dark, but will not show phosphorous acid in the daylight. At 100° Fahrenheit the cooling-power of the 70 wire-gauze will be sufficient to keep the phosphorus from melting or inflaming. If the instrument be kept in a warm room in the winter, it will work at nearly all temperatures. Said instrument is so simple that there will 75 be no difficulty in imparting, even to the most ignorant, the necessary information how to use and take care of it, and the cheapness of its construction will admit of its general employment by all using gas. It can be used in dark 80 places, and will show with safety the presence of gas as surely as a cumbersome and expensive safety-lamp. Nor does the employment of the phosphorus materially affect its durability, inasmuch as a single charge of phosphorus 85 will answer for a very large number of tests, and, should it give out, the phosphorus can readily be replaced, as the cap with its attached gauze disks is readily removable from the tube. There are but few causes that will 90 interfere with the working of the device. If the vapors of turpentine, ether, and other like volatile agents are present, they can be detected by their odor.

Unlike a safety-lamp, in which gauze is used 95 to prevent a flame from passing through it, the gauze in this instrument by its cooling-power is used to wholly prevent a flame.

Having thus described my invention, what I claim as new, and desire to secure by Letters 100 Patent, is—

1. The within-described device for detecting, by the aid or exposure of phosphorus, the presence or escape of gas in a room or else-

where, consisting of a transparent tube having an opening below but mainly closed above, and of a phosphorus-table within the tube, composed of a series of gauze disks adapted to form a close fit within the tube, substantially as specified.

2. The within-described gas-leak detector operating by the aid or use of phosphorus, as specified, the same consisting of the transparent tube A, open below, a removable cap C, having a gauze-covered opening in it and adapted

to close the upper end of said tube, a wire or pendant attached to said cap and arranged to project down within the tube, and a close-fitting phosphorus-carrying table within the tube, composed of a series of wire-gauze disks b, one above the other and attached to said wire or pendant, essentially as herein set forth.

JOHN F. STARK.
